(57) **CLAIM**

The ornamental design for a pod light, as shown and described.

DESCRIPTION

FIG. 1 is a top-front-left perspective view of a pod light showing my new design;

FIG. 2 is a bottom-front-right perspective view thereof;

FIG. 3 is a top-rear-right perspective view thereof;

FIG. 4 is a top-rear-left perspective view thereof;

FIG. 5 is a front elevational view thereof;

FIG. 6 is a rear elevational view thereof;

FIG. 7 is a left-side elevational view thereof;

FIG. 8 is a right-side elevational view thereof;

FIG. 9 is a top plan view thereof; and,

FIG. 10 is a bottom plan view thereof.

The broken lines showing the power cord, battery cover, and internal reflector components are included for the purpose of illustrating portions of the pod light which form no part of the claimed design.

1 Claim, 10 Drawing Sheets
